CONTAINER

James E. Baechle, River Forrest, Ill., assignor to
 American Can Company, New York, N. Y., a
 corporation of New Jersey

Application December 29, 1933, Serial No. 704,581

5 Claims. (Cl. 220—40)

The present invention relates to metallic containers or cans having screw lock covers and has particular reference to a body curl and cover locking key construction for such containers or cans.

5 The invention furthermore contemplates the addition of a frangible seal to a body curl and cover locking key construction so that the original seal for the can may be made by a frangible disc protected by the lock cover, this cover being a secondary seal at such time and becoming a re-
 10 closure member after fracture of the frangible disc.

An object of the invention is the provision of a can having the upper edge of its body formed as 15 a locking curl which cooperates with a formed cover member part to effect a lock joint cover for the can.

Another object of the invention is the provision of an interlocking can and cover having a 20 frangible seal embodied in the can and protected by the cover, this seal being adapted for cutting out to open the can without affecting the interlocking relation of can and cover.

Still a further object of the invention is the 25 provision of a can of the character described having a body curl engagement for a lock cover, the curl being also utilized for the locking engagement with the cover.

Numerous other objects and advantages of the 30 invention will be apparent as it is better understood from the following description, which, taken in connection with the accompanying drawing, discloses a preferred embodiment thereof.

Referring to the drawing: 35 Figure 1 is a perspective view of a can and screw locking cover embodying the present invention;

Fig. 2 is an enlarged perspective view of the 40 cover of such a can;

Fig. 3 is a top plan view of the can with the cover removed and showing a frangible seal disposed in the end of the can;

Fig. 4 is an enlarged fragmentary sectional detail taken at a position relative to the can as 45 indicated by the line 4—4 in Fig. 3 and showing in addition a lock cover partially inserted into the can above its frangible seal;

Fig. 5 is a view similar to Fig. 4 but taken at a position on the can which is indicated by the 50 line 5—5 in Fig. 3, the cover in this view being fully inserted and locked in position; and

Fig. 6 is a fragmentary sectional detail of the 55 can and cover in locked position, the section being taken through one of the locking keys as indicated by the line 6—6 in Fig. 5.

In the drawing there is disclosed as a preferred embodiment of the invention a cylindrical can body 11 having a closed bottom end 12 secured thereto in any suitable manner as by a double seam. The body 11 is formed with an inwardly 5 projecting bead 13 adjacent its upper open end and above the bead the body wall extends up and terminates in an inwardly curled edge 14.

A frangible disc 15 may be used to provide a primary seal for the open end of the can and is 10 preferably formed with an upwardly extending cylindrical flange wall 16. The disc 15 is tightly secured to the can body and when fully inserted and secured in place rests upon the bead 13 with its flange wall 16 engaging within the upper part 15 of the body wall.

The upper edge of the disc flange 16 extends inside of the body curl 14 and the terminal edge of the curl (indicated by the numeral 17) is embedded in the frangible disc flange 16 as illustrated in Figs. 5 and 6. This holds the frangible disc in secure position within the can. The body curl 14 (Figs. 3 and 4) is interrupted at intervals and is flattened into the cross-section shape illustrated in Fig. 4, where it will be observed the 25 circular cross section of the curl 14 is supplanted by a rectangular bend section 18. This construction provides a vertical passage 19 extending through the curl 14, the drawing illustrating four 30 of these passages.

A lock cover 21 is provided for closing the upper end of the can and for protecting the frangible seal 15. This lock cover is formed with a domed top wall 22 which terminates in an overhanging hand grip section 23 that merges in a 35 curved annular wall 24 (Fig. 5) joined to the upper end of a cylindrical wall 26.

The wall 26 is slightly less in diameter than the inside diameter of the curl 14 and so slips easily into the top of the body when the cover 21 40 is put on the can. In this application of the cover to the can, the overhanging section 23 provides a convenient hand grip for easy handling of the cover.

The cover wall 26 is pressed out at intervals 45 to provide inclined interrupted threads or locking keys 27, one end of each key being turned down in a lug 28 and its opposite end turned up in a lug 29. The total width of each locking key 27 is slightly less than the width of the passage 50 19 formed in the flattened part of the curl 14 and when the cover is applied to the can each locking lug 27 passes freely through its passage 19 during the vertical movement of the cover wall 26 inside of the body curl 14. Fig. 4 illus- 55

trates the cover 21 in partially inserted position, this view also showing the location of a locking key 27 relative to its associated curl passage 19.

When in completely inserted position (Figs. 5 and 6) the inclined body portion of each locking key 27 is below the body curl 14. From this inserted position the cover is then locked on the can by relative rotation between can and cover. As such rotation takes place each inclined thread locking key 27 rides under the adjacent edge of the curl 14 at the passage 19 and the wedging action provided by this movement pulls the annular grooved wall 24 of the cover down into close locking engagement on top of the body curl 14.

The upper lugs 28 of the locking keys 27 strike against edges or shoulders 31 (Figs. 3 and 5) of the curl 14 and act as stop elements limiting the amount of rotation of the cover. These edges 31 may be formed by slitting the curl when the flattened sections 18 are produced or the flattened sections may be merely bent sharply enough to provide the edges or shoulders 31.

A can such as the one illustrated in the drawing is preferably filled through its bottom end prior to the application of the bottom onto the body and at such a time the frangible disc 15 is in its fixed position on the other or top end of the can body and the lock cover 21 is also locked in position and protects the disc.

The frictional engagement of the thread locking keys 27 with and beneath the curl 14, when the cover is applied, causes the free end of the curl to bite into the flange 16 of the frangible disc 15, thereby augmenting the secure attachment of the latter to the can body walls during initial filling and assembly of the parts.

When the sealed and filled can is to be opened the lock cover need only be rotated back relative to the can body and lifted vertically from its assembled position. This exposes the frangible disc 15 which may then be cut out by a knife or other sharp instrument to open the can. After the disc 15 has been broken the lock cover 21 may be used as a reclosure and this then provides a secondary seal for the can when applied and locked in place.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A sealed container, comprising a cylindrical body having a continuous inwardly curled edge at one end, said curled edge being flattened at intervals to provide vertically extending passages, and a lock cover having a vertical cylindrical wall adapted to enter into the curled end of said body when said cover is applied to close the container, said cover wall being pressed out at intervals to form inclined locking keys which pass through the said passages of said curled body edge during the application of the cover, said keys being adapted to engage under adjacent curled body sections upon relative rotation between body and cover to lock the matter in closing position, the upper ends of said locking keys terminating in upstanding stop lugs engageable with the curl at one end of each of

said passages to limit relative rotation between the container and cover.

2. A sealed container, comprising a cylindrical body having an open end, a frangible sealing disc located inside of the open end of said body and closing the same, the upper edge of said body terminating in a continuous inwardly extending curl the free edge thereof providing a holding engagement with the outer edge of said disc, said curled edge also being interiorly flattened at intervals to provide vertically extending passages, and a lock reclosure cover having a vertical cylindrical wall adapted to pass inside of the said body curl when the cover is applied to the container, said cover wall having locking keys located at spaced intervals and on the outside of the wall which are adapted to pass through the said passages of said curled body edge during the application of the cover, said keys extending below said body edge curl and engaging under it when the cover is fully seated and turned relative to the body, thereby drawing the cover into close engagement with the top of said body curl, the pressure of said cover keys on said body curl forcing the free edge of the latter into tight holding engagement with the outer edge of said frangible sealing disc.

3. A sealed container, comprising a cylindrical body having an open end, a frangible sealing disc located inside of the open end of said body and having its edge turned up in a cylindrical flange which tightly engages the wall of said body closing the open body end, the upper edge of said body terminating in a continuous inwardly extending curl the free edge thereof providing a holding engagement with the flange of said disc, said curled edge also being interiorly flattened at intervals to provide vertically extending passages, and a lock reclosure cover having a vertical cylindrical wall adapted to pass inside of the said body curl when the cover is applied to the container, said cover wall having inclined locking keys located at spaced intervals and on the outside of the wall, said keys terminating at their upper ends in upstanding stop elements and being adapted to pass through the said passages of said curled body edge during the application of the cover, said keys extending below the said body edge curl and engaging under it when the cover is fully seated and turned on the body, the said key stop elements engaging against the end walls of the body curl portions and limiting relative rotation of said cover and body, the pressure of said cover keys on said body curl forcing the free edge of the latter into tight holding engagement with the outer edge of said frangible sealing disc.

4. A sealed container, comprising a cylindrical body having a continuous inwardly curled edge at one end, said curled edge being flattened at intervals to provide vertically extending passages partially defined by a reinforcing wall of double thickness, and a lock cover of thin sheet material having an overhanging top merging into a vertical cylindrical wall smaller in diameter than the inside diameter of said body curl, said cover wall being adapted to enter into the curled end of said body when said cover is applied to close the container, said cover wall being pressed out at intervals to form locking keys which pass through the said passages of said curled body edge during vertical movement of said cover as it is applied to the body, the said keys being adapted to engage under adjacent curl body sections upon relative rotation between body and cover to draw the said cover top down on said body curl.

and to thereby lock the cover in closing position, said overhanging top of the cover projecting over and beyond said curled edge of the body to provide a hand hold for conveniently manipulating the cover.

5. A sealed container, comprising a cylindrical body having an internal bead formed adjacent an open end, a frangible sealing disc located inside of the open end of said body and resting upon 10 said body bead, the upper edge of said body having a continuous curl to provide a holding engagement with the outer edge of said disc, said curled edge also being interiorly flattened at intervals to provide vertically extending passages through 15 said curl, and a lock reclosure cover having a vertical cylindrical wall pressed outwardly at

intervals to provide inclined interrupted thread locking keys, each key having a total width less than the width of a said curl passage, said locking keys being adapted to pass through the said passages of said curled body edge during the application of the cover to the container, relative rotation of the inserted cover and body thereupon bringing the said inclined thread keys beneath said body curl with a wedging action to draw said cover into locking position on said body 10 and over said frangible sealing disc, the pressure of said cover keys on said body curl forcing the free edge of the latter into tight holding engagement with the outer edge of said frangible sealing disc. 15
